UNITED STATES PATENT OFFICE.

JOHN F. GAIL, OF KENOSHA, WISCONSIN, ASSIGNOR TO THE SIMMONS MANUFACTURING COMPANY, OF SAME PLACE.

SPRING BED AND SEAT BOTTOM.

SPECIFICATION forming part of Letters Patent No. 639,224, dated December 19, 1899.

Application filed January 16, 1899. Serial No. 702,350. (No model.)

To all whom it may concern:

Be it known that I, JOHN F. GAIL, a citizen of the United States, residing at Kenosha, in the county of Kenosha and State of Wisconsin, have invented a new and useful Spring Bed and Seat Bottom, (Case C,) of which the following is a specification.

For convenience in making cross-reference this application is designated "Case C," and 10 four other applications for Letters Patent for bed-bottoms executed by me of even date herewith are designated, respectively, "Case A," "Case B," "Case D," and "Case E."

This invention relates particularly to 15 spring bed-bottoms formed of vertical spiral springs united horizontally by tie-rods.

The improvement involves the use of a new form of tie-rod which permits the use of the simplest form of vertical spiral springs and 20 which allows the ready assembling of the parts of the bed-bottom to constitute the finished structure. There is economy in the ready assembling of these parts, and there is also economy in the use of a simple form of 25 the spiral spring.

My improvement results in a structure which has a high degree of strength, a distribution of strain applied at any particular point, and an even surface.

30 In the accompanying drawings, Figure 1 is a plan of a portion of a bed-bottom embodying my improvement. Figs. 2 and 3 are detail views of the construction shown in Fig. 1. Figs. 4, 5, 6, and 7 illustrate modifications.

Inasmuch as the general construction of bed-bottoms of this class is well known, I deem it sufficient to illustrate only portions of bed-bottoms showing the application of my improvement.

40 Referring first to Figs. 1 and 2, A is a rectangular frame forming the margins of the bed-bottom. This frame may be of wood or metal; but it is preferably made of metal rods or bars somewhat heavier than the metal of the springs and tie-rods.

45 B are the springs. These are arranged in rows parallel to the sides of the frame A and are in vertical position and of spiral form, the 50 upper end of each being formed into a com-

plete ring B' by knotting or in any other suitable manner. The springs may be cylindric in outline or they may be conical or double conical. As already stated, it is the object of the invention to embody the well-known 55 forms of vertical springs into a bed-bottom of superior quality and the parts of which may be readily made and readily assembled.

C is a tie-rod extending transversely across the bed-bottom and over one row of springs, 60 near the edges of the latter, and having its ends suitably attached to the frame A. At each spring said tie-rod has three upward bends C', two over the ring B' and one midway between said two. Said two upward 65 bends may be so great as to allow the main portion of the tie-rod to rest below the level of the ring B'.

C² are loops extending laterally from the tie-rod C at each spring B to the adjacent 70 spring of the next row or to the side of the frame. Each loop is formed by folding wire into substantially a V shape, the two ends of the wire extending beneath the ring B' and thence over and around the tie-rod C, preferably 75 at one of the bends C'. The portion of the loop the farther from the tie-rod C is bent into vertical form (marked C³) and passes beneath and then upward through the ring B' of the adjacent spring of the next row of 80 springs.

The transverse row of springs B adjoining the frame A are united to said frame by one of the tie-rods C, the loops C² extending partially around the said frame.

85 Another set of tie-rods D D, for convenience designated as "key-rods," are arranged at right angles to the tie-rods C. These are straight (though they may be crimped at points where they bear on other parts, as 90 shown in Fig. 7) and extend centrally over the longitudinal rows of springs B and beneath the vertical part C³ of each loop C² in the row of springs traversed by said key-rod. The ends of the key-rod D may be suitably 95 secured to the frame A, preferably in engagement with a loop C², engaging the frame at that point, the rod reaching through the loop.

It will now be seen that the bed-bottom 100

herein described consists of only five kinds of parts—namely, the frame A, the springs B, the tie-rods C, the loops C², and the key-rods D; and it will now be understood that the assembling of these parts to form a complete bed-bottom is a simple process involving only the use of the hands and a simple bending-tool for securing the ends of the tie-rods and key-rods. The frame may be first put into position and the springs then placed in rows within the frame and the tie-rods C then put into position with reference to the springs and the frame and the ends of said tie-rods bent around the frame or secured in any suitable manner. The loop C² may be applied to the tie-rod C before the latter is applied to the frame and springs or after the tie-rod is in position.

In Fig. 5 the loop C² after passing beneath the ring and over the tie-rod passes onward and again beneath the ring and then around the tie-rod.

In Figs. 4, 6, and 7 the vertical part C³ of the loop is turned downward instead of upward. This requires the key-rod to pass beneath the adjacent spring-ring and through said part of the loop.

In Fig. 6 the tie-rod C passes beneath the spring-ring, and the loop C² extends over or upward through said spring-ring.

The key-rods D may have their ends secured to the frame, as shown in Fig. 1. This results in a very positive interconnection of the springs and the forming of such a surface as will not yield unduly at any one point, pressure at any point involving the depression of a considerable area of the bed-bottom surface. The fact is also to be noted that the key-rods D, extending midway over the rings B, prevent the central portion of the spring from pushing upward through the ring B', as is sometimes the case when the upper portion of the spring is left unprotected.

It should be noted that the loops pass or enter the plane of the spring-ring only far enough to let the key-rods pass under strain.

It will be understood that the number of tie-rods C will depend upon the number of rows of springs extending in the direction of said tie-rods.

It will also be understood that my invention may be applied to spring-seats and that the foregoing description is applicable to spring-seats as well as to spring bed-bottoms.

The constructions shown herein in Figs. 2, 3, and 5 are also described, but not separately claimed, in the application designated as "Case A," to which reference has been made. The form illustrated herein by Fig. 5 is specifically claimed (in comparison with the claims herein made) in "Case D," and in "Case E" there is illustrated, but not separately claimed, a construction embodying the features (as to the loop) illustrated by Figs. 2 and 5 of this application.

No specific claim is herein made for a key-

rod having a bend where it crosses the ring of the spring, as illustrated in Fig. 7 of this application. This feature is claimed in "Case E," filed simultaneously with this application. 7c I claim as my invention—

1. The combination of spiral springs having their ends formed into rings, single, parallel tie-rods extending across said springs, lateral loops consisting of a piece of wire folded and secured to said tie-rods and extending through the rings of one row of springs and thence laterally and vertically through the rings of the adjacent row of springs, and key-rods arranged transversely to the said tie-rods and extending midway along the rows of springs and through said loops where the latter extend through the spring-rings, substantially as shown and described. 75 80

2. The combination of spiral springs having their ends formed into rings, single, parallel tie-rods extending across said springs, lateral loops consisting of a piece of wire folded and secured to said tie-rods and extending downward through the rings of one row of springs and thence laterally beneath and upward through the rings of the adjacent row of springs, and key-rods arranged transversely to the said tie-rods and extending midway along rows of springs and beneath said loops 90 where the latter extend through the spring-rings, substantially as shown and described. 95

3. The combination of a rectangular frame, spiral springs having their ends formed into rings, single, parallel tie-rods extending across said frame, lateral loops consisting of a piece of wire folded and secured to said tie-rods and extending downward through the rings of one row of springs and thence laterally beneath and upward through the rings of the adjacent row of springs, and key-rods arranged transversely to the said tie-rods and extending midway over rows of springs and beneath said loops where the latter extend through the spring-rings, substantially as shown and described. 105 110

4. The combination of spiral springs having their ends formed into rings, single, parallel tie-rods extending across said springs, lateral loops consisting of a piece of wire folded and secured to said tie-rods by bending around said rods and extending through the rings of one row of springs and thence laterally and vertically through the rings of the adjacent row of springs, and key-rods arranged transversely to the said tie-rods and extending midway over rows of springs and through said loops where the latter extend through the spring-rings, substantially as shown and described. 115 120 125

5. The combination of a rectangular frame, spiral springs having their ends formed into rings, single, parallel tie-rods extending across said frame and springs, lateral loops consisting of a piece of wire folded and secured to said tie-rods by bending around said rods and extending downward through the rings of one 130

row of springs and thence laterally beneath and upward through the rings of the adjacent row of springs, and key-rods arranged transversely to said tie-rods and extending midway over rows of springs and through said loops where the latter extend through the spring-rings, substantially as shown and described.

6. The combination of a rectangular frame, spiral springs having their ends formed into rings, single, parallel tie-rods having upward bends and extending across said frame, lateral loops consisting of a piece of wire folded and secured to said tie-rods and extending downward through the rings of one row of springs and thence laterally and vertically beneath and upward through the rings of the adjacent row of springs, and key-rods arranged transversely to said tie-rods and extending midway over rows of springs and through said loops where the latter rise through the spring-rings, substantially as shown and described.

7. The combination of spiral springs having their ends formed into rings, single, parallel tie-rods having upward bends and extending across said springs, lateral loops consisting of a piece of wire folded and secured to said rods by bending around said rods and extending through the rings of one row of springs and thence laterally and vertically through the rings of the adjacent row of springs, and key-rods arranged transversely to said tie-rods and extending midway over rows of springs and through said loops where the latter extend through the spring-rings, substantially as shown and described.

8. The combination of a rectangular frame, spiral springs having their ends formed into rings, single, parallel tie-rods extending across said frame, lateral loops consisting of a piece of wire folded and suitably secured to said tie-rods and extending downward through the rings of one row of springs and laterally beneath and upward through the rings of the adjacent row of springs, and key-rods arranged transversely to said tie-rods and extending midway over rows of springs and beneath said loops where the latter rise through the spring-rings and key-rods having their ends suitably attached to said frame, substantially as shown and described.

9. The combination of a rectangular frame, spiral springs having their ends formed into rings, single, parallel tie-rods extending across said frame, lateral loops consisting of a piece of wire folded and secured to said tie-rods by bending around said rods and extending downward through the rings of one row of springs and laterally beneath and upward through the rings of the adjacent row of springs, key-rods arranged transversely to said tie-rods and extending midway over rows of springs and beneath said loops where the latter rise through the spring-rings and said key-rods having their ends suitably attached

to said frame, substantially as shown and described.

10. The combination of a rectangular frame, spiral springs arranged in rows and having their ends formed into rings, single, parallel tie-rods extending across said frame and springs lateral loops consisting of a piece of wire folded and suitably secured to said tie-rods and extending through the rings of one row of springs, thence laterally and vertically through the rings of an adjacent row of springs, and one such tie-rod parallel to the others and having similar loops extending through the rings of a marginal row of springs and engaging the adjacent portion of said rectangular frame, and key-rods arranged transversely to the said tie-rods and extending along said springs and through said loops, substantially as shown and described.

11. The combination of a rectangular frame, spiral springs arranged in rows and having their ends formed into rings, single, parallel tie-rods extending across said frame and springs lateral loops consisting of a piece of wire folded and suitably secured to said tie-rods and extending through the rings of one row of springs, thence laterally and vertically through the rings of an adjacent row of springs, and one such tie-rod parallel to the others and having similar loops extending through the rings of a marginal row of springs and engaging the adjacent portion of said rectangular frame, and key-rods arranged transversely to the said tie-rods and extending along said springs and through said loops and around the sides of said frame, substantially as shown and described.

12. The combination of a side of a frame, a row of spiral springs arranged parallel to said side and having their ends formed into rings, a tie-rod extending parallel to said row of springs, lateral loops consisting of a piece of wire folded and suitably secured to said tie-rods and extending downward through said springs and around said side of the frame, and key-rods arranged transversely to said tie-rods and extending midway over said springs and through said loops and around said side of the frame, substantially as shown and described.

13. The combination of a rectangular frame, spiral springs having their ends formed into rings, single, parallel tie-rods extending across said frame, lateral loops consisting of a piece of wire folded and extending through the rings of one row of springs and laterally and vertically through the rings of the adjacent row of springs, the ends of said loops passing through the rings against which the tie-rods rest and being then attached to said tie-rods, and key-rods arranged transversely to said tie-rods and extending midway over rows of springs and through said loops where the latter extend through the spring-rings, substantially as shown and described.

14. The combination of a rectangular frame,

spiral springs having their ends formed into rings, single, parallel tie-rods extending across said frame, lateral loops consisting of a piece of wire folded and extending downward through the rings of one row of springs and laterally beneath and upward through the rings of the adjacent row of springs, the ends of said loops passing beneath the rings against which the tie-rods rest and being then attached to said tie-rods and key-rods extending mid-

way over rows of springs and beneath said loops where the latter rise through the spring-rings, substantially as shown and described.

In testimony whereof I affix my signature in presence of two witnesses.

JOHN F. GAIL.
